DEVICE FOR WINDING A PLURALITY
OF LINES AT RELATIVELY IRREGULAR
SPEEDS ABOUT A COMMON SHAFTElmer Shelton Knight, Cordova Bay,
British Columbia, Canada

Application May 9, 1945, Serial No. 592,887

3 Claims. (Cl. 254—184)

1

My invention relates to an improvement in mechanical movements which is adapted to move two or more objects at indeterminate speeds one to the other.

Animated displays such as are used in exhibitions or store windows for the purpose of attracting attention frequently fail in their appeal due to the regularity of relative movement between such moving figures representing people or animals in the display, whereas if all these figures could be made to move at totally indeterminate speed where one may first pass another and later lag behind, the interest in the display would be far more lasting. Other displays using translucent screens where different coloured lights are flashed on and off at predetermined intervals fail to attract attention for long on account of the regularity of change of the lighting effects.

The objects of the present invention are to provide means for moving figures along defined paths, or tripping switches in a plurality of circuits in an irregular manner, so that infinite variety of change is effected in the display and the interest created by said display will be materially enhanced and prolonged.

The invention contemplates a plurality of reels adapted to be driven in unison, a flexible member attached to each reel and a mechanism adapted to cause a variation in the speed in which some of the members are being wound upon their reels during the rotation of said reels, as will be more fully described in the following specification and shown in the accompanying drawings, in which:

Fig. 1 is a sectional view of the invention showing its adaptation to an animated display device.

Fig. 2 is a plan view of the invention.

Fig. 3 is a sectional view of the track along which the flexible members are adapted to be drawn and the manner of attaching a display figure to said members.

In the drawings like characters of reference indicate corresponding parts in each figure.

The numeral 1 indicates a horizontal panel or base of a display 2 which is mounted in front of a background 3 on which a suitable scene is displayed. At one end of the base 1 is a frame 4 consisting of side walls 5 suitably spaced apart. The frame will preferably be enclosed and so treated as to represent a building in keeping with the scene displayed upon the background, such as a barn or small building 7.

Mounted between the walls 5 of the frame 4 are four shafts respectively numbered 9, 10, 11

and 12 and the shafts 9 and 10 are not necessarily rotatable. The shaft 12 is fitted with a roller generally indicated by the numeral 15 which is secured thereto and is divided into a plurality of reels 16 which are spaced apart by grooves 17. Each groove can serve as a roller or winding drum 18 which is provided with one or a pair of inclined side walls 19, each side wall is obviously in the nature of a truncated cone. The shaft 12 is fitted with a pulley 20 by which it may be driven from a suitable source of power. A plurality of guides 22 are slidably mounted upon the shaft 10. These guides consist of a sleeve 23 with spaced flanges 24 which are connected together with a pin 25 set a distance from the sleeve 23, so as to afford free passage between said sleeve and pin of a flexible member or cord 27. In the embodiment shown in Figure 2, three spools 15 are shown and to each a cord is attached, for the purpose of identification these three cords will be referred to as 27A, 27B and 27C.

The base 1 is provided with parallel channels 28 which are aligned with the centre of the reels 16 to accommodate the free end of the cords 27 and figures 29, such as a girl and some ducks, are mounted on bases 30 and are preferably fitted on their rear sides with spring clips 31 for attaching each of the figures to their respective cords 27. It will be noted that each cord passes along its channel to a point adjacent the frame 4 where it is held against lifting by a keeper 32, from thence it would normally extend in a straight line to and around the shaft 9 forming a run E, thence back to and around the sleeve 23 of a guide 22 forming a run F upon which it would be held against removal by the pin 25 and then pass to its aligned reel 16, forming a run G. If nothing were provided to interfere with the free running of the cords 27 from the platform to their respective reels 16, the runs E, F and G of each cord would lie in a single vertical plane and when all the reels were rotated in unison to wind up the cords the free ends of each or any figure or device attached to a cord would travel along the platform 1 at identical speed. I therefore provide the shaft 11 with free sliding and rotational movement between the walls 5 and provide a plurality of radial fingers 33 round about the shaft, each of which are capable of being brought into contact with a flange 24 of a guide 22 on the shaft 10. These radial fingers are spaced at regular degrees of angularity about the shaft and disposed longitudinally of the shaft at dif-

ferent distances apart to those of the reels 16, as for instance, where eight reels and cords are provided, nine or eleven sets of fingers 33 would be desirable, a set of fingers being assumed to be the number of adjacent fingers within 360 degrees or four as shown in Figures 1 and 2. The outer end of the shaft 11 is provided with a knurled knob 34 for the purpose of imparting to said shaft both rotational and sliding movement.

The operation of the invention as applied to a display such as illustrated, the figures 29 would be drawn back to their starting point by any appropriate means and the shaft 11 would be rotated and moved endwise in any manner desired, the movement being momentary or otherwise. The effect of the movement of the shaft 11 would be to cause some of the guides 22 to be moved from their last position of rest upon the shaft 10 and throw the runs F and G of the cord 27 of each of said displaced guides out of substantial horizontal parallelism with their runs E, so that when said cords are being wound about the shaft 12, it is possible for one to continue to wind onto its reel 16 and simultaneously for another to run off the side edge of its reel and wind onto the base of the groove 17, thus reducing the winding speed of said cord due to the reduced dimension of the part upon which it is winding. If a given guide is held against endwise movement of its shaft 10 and its cord, after feeding onto its reel, slides off onto the base of the adjacent groove, a disalignment will occur which may cause the line to wind back upon itself to correct the disalignment and start to climb back up on the sloping side wall of said groove towards its reel, in which case a cord will be wound in a volute around said wall and will be moving inward at a progressively increasing speed over that which existed when winding around the base of the groove.

It will be obvious that the progression of the several cords will vary as their runs E, F and G diverge or converge horizontally in respect to the line of their channels and that due to the tendency of one coil being wound on a cylindrical surface to wind in contact with the previous coil, so that the alignment of the runs E, F and G will be affected and the speed of travel of the cord be rendered totally indeterminate.

What I claim as my invention is:

1. A mechanical movement comprising a plurality of winding drums all adapted to be rotated in unison at predetermined peripheral speeds, said winding drums having winding areas of different diameters, a flexible member attached to each winding drum to be wound thereon, means spaced from said drums for aligning the several flexible members onto their drums adjacent their point of attachment, a shaft extending across the flexible members and guides slidable along said shaft, each guide being engaged by one of the

flexible members in the interspace between the aligning means and their drums, and slidable means for engaging some of the guides to move them lengthwise of the shaft and to disalign their attached flexible members to cause said members to wind upon different areas of their respective drums, said slidable means having a plurality of staggered fingers each adapted to be moved to contact one or more guides.

10 2. A mechanical movement comprising a shaft having a plurality of drums and a plurality of annular grooves between said drums, said drums and grooves being rotatable as a unit, the sides of the grooves being in the form of truncated cones, 15 flexible members connected to some of said drums to be wound thereon, means for normally aligning said members at right angle to the drum shaft, a shaft parallel to the drum shaft and guides slidable upon said shaft, each of said guides being engaged by one of the flexible members between the aligning means and its drum, and slid- 20 able means for moving any of the guides to effect disalignment of its flexible member, whereby to cause said member to slip upon its adjacent cone, 25 said slidable means having a plurality of stag- gered fingers, each adapted to engage one or more of the guides.

3. A mechanical movement comprising a shaft having a plurality of drums and a plurality of annular grooves between said drums, said drums and grooves being rotatable as a unit, the sides of the grooves being in the form of truncated cones, 30 flexible members connected to some of said drums to be wound thereon, means for normally aligning said members at right angle to the drum shaft, a shaft parallel to the drum shaft and guides slidable upon said shaft, each of said guides being engaged by one of the flexible members between the aligning means, and its drum, 35 aligning said members at right angle to the drum shaft, a shaft parallel to the drum shaft and guides slidable upon said shaft, each of said guides being engaged by one of the flexible members between the aligning means, and its drum, 40 and means for moving any of the guides to effect disalignment of its flexible member, said disaligning means consisting of a shaft mounted for sliding and rotational movement, said shaft hav- 45 ing a plurality of fingers radially disposed to project into the path of the several guides, each of said guides having one or more finger engaging contacts.
